UNITED STATES PATENT OFFICE.

JAMES JARVIS PREBLE, OF NEWTON, MASSACHUSETTS, ASSIGNOR TO SPRAY ENGINEERING COMPANY, OF BOSTON, MASSACHUSETTS, A CORPORATION OF MASSACHUSETTS.

FILTER-CELL-WASHING MACHINE.

Application filed November 6, 1925. Serial No. 67,263.

The present invention relates to washing machines, and more particularly to a washing machine for removing the dust and dirt retained on the filtering media of an air filter cell.

Air filters are now in wide general use for eliminating the small, solid particles, called dust, floating in a gas, such as atmospheric air or a gas produced in a manufacturing process. While innumerable materials and forms thereof have been proposed heretofore for the elimination of the injurious dust, a standard cell for holding the filtering media has been developed. This standardized cell comprises a metallic box having expanded metal covers for the inlet and outlet openings thereof between which the filtering media is placed and a pair of handles to facilitate the insertion of the cell into and its removal from the bank of cells making up the filter installation. This bank of cells comprises a plurality of the cells arranged in tiers. To maintain the filter installation in efficient operation it is necessary to remove for cleaning a few of the dirty cells at a time and to replace them with clean cells. Usually the dirty cells are removed for cleaning in accordance with a definite schedule. That is, in a filter installation containing, for instance, thirty cells made up five tiers of six cells each, five dirty cells are removed for cleaning every five days. The operator engages the handles of the removed dirty cells and dips them repeatedly in a bath of hot water and caustic soda. As each cell weighs thirty pounds the labor of cleaning the cells is considerable. Experience demonstrates that owing to this labor the duty of cleaning the cells is often neglected. It has been proposed to wash the dirty cells in a power-driven machine having a capacity to receive a plurality of dirty cells for cleaning in a single operation. Bearing in mind that only a few cells are cleaned at a time with intervals of days between cleaning operations, it is apparent that the power-driven machine would be used too infrequently to warrant the expense of its installation. It is a fact, however, that it is highly desirable to provide some apparatus to relieve the workmen of the heavy duty of cleaning the dirty cells thus to insure their proper cleaning in strict accordance with the cleaning schedule.

The object of the present invention is to provide a washing machine for cleaning dirty filter cells which will be simple in construction and mode of operation and thus cheap to manufacture, and by which the workman may clean the dirty cell with ease and celerity.

To the accomplishment of this object or objects, and such others as may hereinafter appear, the features of the present invention relate to certain devices, combinations and arrangements of parts, hereinafter described, and then set forth broadly and in detail in the appended claims.

The various features of the invention will be readily understood from an inspection of the accompanying drawings illustrating the best form of the invention at present known to the inventor, in which,

Figure 1 is a plan of the washing machine with the tank cover removed;

Fig. 2 is a perspective of the filter cell, and

Fig. 3 is a sectional elevation of the washing machine, the tank cover being disassociated therefrom.

The filter cell to be cleaned comprises a metal box 4 (Fig. 2) within which the filtering media is positioned. The inlet opening 5 is surrounded by a flange 6 provided with the handles 7 and 8 to facilitate handling.

The washing machine for cleaning the filtering media in the filter cell comprises a metal tank 9 supported on legs 10 and provided with a cover 11 the flange 12 of which rests on a ledge 13 surrounding a rectangular opening 14 to the interior of the tank. The bottom of the tank slopes towards one corner thereof so that the tank may be drained through a valve 15.

Secured to the opposite sides of the interior of the tank are the bearings 16 and 17 for a pair of stub shafts 18 and 19. The stub shafts are secured respectively to couplings 20 and 21 carried by the opposite end faces of a holder 22 for the filter cell.

The sides 23 of the holder are open to permit the hot water and caustic soda with which the tank 9 is partially filled free access to the interior of the holder. As shown in Figs. 1 and 3 the holder is of a size to receive within it the filter cell illustrated in Fig. 2. The filter cell is inserted by the

workman who grasps the handle 8 in one hand and then lowers the cell into the holder.

The cell is clamped in place within the holder by a bar 24 pivoted at one end to the holder and provided at its other end with a slot 25 to embrace a screw 26 pivoted on the holder and engaged by a wing nut for securing the bar 24 in the positions of Figs. 1 and 3.

10 The holder is rotated to cause the hot water and caustic soda within the tank to surge through the filtering media in the cell by a crank 27 on the free end of the stub shaft 19 which extends through the side wall

15 of the tank 9. The bearing 17 and stub shaft 19 are packed to prevent leakage therebetween by a suitable packing device indicated at 28 (Fig. 3).

It is usually necessary to thoroughly clean 20 the cell to impart to the holder a few revolutions in one direction when its direction of rotation is reversed in order to rotate it several times in the other direction. To remove the clean cell it is only necessary to 25 remove the cover 11, unfasten the bar 24 and swing it out of the way.

What is claimed as new, is:

1. A filter cell washing machine having, in combination, a tank for washing fluid, a holder rotatably mounted within the tank 30 and constructed to receive a single filter cell, said holder having solid bottom and end faces and open top and side faces, means for barring the open top of the holder for keeping the filter cell within the holder during the rotation thereof, and a device outside the tank for rotating the holder.

2. A filter cell washing machine having, in combination, a tank for washing fluid, a holder rotatably mounted within the tank 40 and constructed to receive a single filter cell, said holder having solid bottom and end faces and open top and side faces, a bar pivoted on the holder and arranged to extend across the open top of the holder for 45 keeping the filter cell within the holder during the rotation thereof, means for locking the bar in keeping position, and a device outside the tank for rotating the holder.

In testimony whereof I have signed my 50 name to this specification.

JAMES JARVIS PREBLE.
